UNITED STATES PATENT OFFICE.

JAMES MINOR WORKMAN, OF GREENVILLE, SOUTH CAROLINA.

AUTOMOBILE-TOP.

1,128,458.

Specification of Letters Patent.

Patented Jan. 5, 1915.

Application filed April 7, 1912. Serial No. 759,519.

To all whom it may concern:

Be it known that I, JAMES MINOR WORKMAN, a citizen of the United States, residing at Greenville, in the county of Greenville and State of South Carolina, have invented a new and useful Automobile-Top, of which the following is a specification.

The present invention appertains to vehicle or automobile tops, and aims to provide a novel and improved folding top.

It is the object of the present invention to provide a folding top for vehicles embodying side curtains which may be folded with the top.

Another object of the present invention is to provide a top of the character indicated embodying a plurality of ribs or bows which are adapted to fold together, in combination with side curtains slidably carried by the ribs or bows and which are adapted to be slid into the crowns of the ribs or bows to fold with the top and to permit the curtains to be raised so as to open the entrance ways.

Another object of the present invention is to provide a novel frame for each curtain, which shall permit each curtain to be slid upwardly and downwardly and to fold with the top, and which shall maintain the curtains substantial when the top is unfolded.

A further object of the present invention is to provide curtains of the character indicated, which shall have foldable window light frames.

A still further object of the present invention is to provide novel means for slidably connecting the edges of the curtains, or the edge pieces of the curtain frames, to the ribs or bows, so that the curtains may be raised and lowered.

It is also the object of the present invention to provide novel means for folding the top, and for unfolding or erecting it.

With the foregoing general objects outlined, and with other objects in view, which will be apparent as the nature of the invention is better understood, the present invention resides in the combination and arrangements of parts and in the details of construction hereinafter described and claimed, it being understood that changes in the precise embodiment of the invention herein disclosed can be made within the scope of what is claimed without departing from the spirit of the invention.

The preferred embodiment of the invention

has been illustrated in the accompanying drawings, wherein similar reference characters denote corresponding parts, and wherein:

Figure 1 is a side elevation of the top as applied to the body of an automobile, the top being unfolded or erected. Fig. 2 is a fragmental side elevation of the rear portion of the automobile body showing the top in folded or collapsed condition. Fig. 3 is a transverse section of the top when unfolded, taken on the line 3-3 of Fig. 1. Fig. 4 is a side elevation of the peak frame. Fig. 5 is a fragmental plan view of the peak frame. Fig. 6 is a fragmental elevation of the first two ribs or bows. Figs. 7 and 8 are fragmental elevations, giving two different views, of the third or pivoted rib or bow. Fig. 9 is an enlarged transverse section of either the second or third ribs or bows. Figs. 10 and 11 are fragmental elevations, giving two different views, of the rear or fourth rib or bow. Fig. 12 is a transverse section of the fourth or rear rib or bow. Fig. 13 is a fragmental elevation of the curtain frame. Fig. 14 is a fragmental detail of the curtain frame. Fig. 15 is a section detail taken through one of the bows or ribs and the curtain frame. Fig. 16 is a sectional detail. Figs. 17, 18 and 19 are fragmental views showing certain modified rib or bow irons. Fig. 20 is a fragmental view showing a modified form of the rib or bow. Fig. 21 is a cross section of the rib or bow illustrated in Fig. 20, taken through the upright or stile thereof. Fig. 22 is a cross section similar to Fig. 21 taken through the crown or intermediate portion of the rib or bow.

In carrying out the invention, reference being had in detail to the drawing, there are provided a plurality of bows or arched ribs, in this case four, although it is to be understood that any number of bows or ribs may be employed, according to the particular vehicle to which the top is to be applied.

The numeral 1 designates the front or first bow; the numeral 2 designates the second bow; the numeral 3 designates the third or pivoted bow; and the numeral 4 designates the rear or fourth bow.

On the crowns or intermediate portions of the bows or ribs there is secured a cover or canopy 5 of flexible waterproof material, such as pantasote, rubberized cloth or the like. The cover 5 extends into a peak 6 at its forward end, which is supported by a

frame 7 carried by the front or first bow 1.

The first and second bows are connected by folding braces 8; the second and third bows are connected by the folding braces 9; and the third and fourth bows are connected by the folding braces 10; the folding braces being pivoted to the respective bows adjoining the crowns thereof, or at the upper ends of the uprights or stiles of the bows. Each of the braces embodies two sections pivoted to the respective bows and connected by a knuckle joint, so that the sections may fold together downwardly when the top is folded or collapsed. The braces 8, 9 and 10 are disposed on the exterior, while a pair of folding braces 11 connect the third or pivoted bow 8 and the rear top irons 12 carried by the vehicle body at the sides of the rear seat, the braces 11 being disposed on the interior. The braces 11 stand diagonally when the top is erected, or connect the rear top irons 12 with the inner sides of the upper ends of the stiles or uprights of the third or pivoted bow 3. The braces 11 each embody two sections pivoted to the bow 3 and the respective iron 12 and connected by a knuckle joint so that the sections may fold together downwardly and forwardly. If the respective folding braces 8 and 9 were independently pivoted to the respective bows, it would be evident that a person moving the first and second bows back and forth would have some difficulty in doing so, for the reason that there would be nothing to constrain the two sides of the bows to move together or in unison. In order to overcome this disadvantage, the shafts 8^a and 9^a have been journaled through the uprights of the first and second bows, the forward sections of the braces 8 being attached rigidly to the shaft 8^a and the forward sections of the braces 9 being attached rigidly to the shaft 9^a, while the other sections of the said braces are connected loosely to the shaft 9^a and the bow 3, respectively. Thus, the folding braces 8 and 9 will be constrained to fold simultaneously at the opposite sides, so that if one upright of each of the first and second bows is moved forwardly or rearwardly, the other or opposite upright will be moved therewith, thereby avoiding binding or other difficulty in folding and unfolding the top. Similar shafts 56 may be attached to the third and fourth bows, they having no function, further than to brace the bows and to serve as a pivot for the respective braces.

A pair of side curtains 13 are slidably carried by the first and second bows; a pair of similar curtains 14 are carried by the second and third bows; and similar curtains 15 are carried by the third and fourth bows. Each of the curtains is constructed of suitable flexible rainproof material, preferably simi-

lar to the cover or canopy 5, and also embodies a flexible metallic frame 16 to which the said material is secured, the frame and fabric having a pair of openings over which are secured transparent panels 17 of flexible material. 70

A track 18 is secured to each side of a vehicle body along the upper edge, the tracks being preferably or necessarily constructed in sections carried by the doors and respective stationary walls of the body. When the doors are closed, the track sections will be in alignment so as to provide a continuous track from the first bow to the third bow. 75

To the ends of the first and second bows 1 and 2 there are secured the bow or rib irons 19 and a pin 20 is passed slidably through each iron 19, and carries a track engaging member 21 at its inner end. The members or slides 21 slidably engage the track 18, and the pins 20 permit the slides 21 to move to and from the rib irons 19 should the tracks not be parallel, as would be the case with vehicle bodies narrower at 80 the front than the rear. To the ends of the third or pivoted bow 3, there are secured the bow or rib irons 22, which are pivoted to the sides of the vehicle body, the irons 22 having track extensions 23, which ordinarily align with the track proper 18, that is, when the top is erected or unfolded. 85

The rear or fourth bow is supported from the rear top irons 12 by means of a pair of arms or links 24, which are pivoted to the uprights or stiles of the bow 4 at an intermediate point and which are pivoted to the outer ends of the rear top irons 12. The arms or links 24 permit the rear or fourth bow 4 to swing rearwardly and downwardly 100 against the third or pivoted bow 3, when the top is folded, as will be seen in Fig. 2, and when the bow 4 is erected, the arms or links 24 will stand almost erect, the bow 4 carrying stops 25 adapted to contact with the 105 arms or links 24 to limit the forward movement of the bow 4 when the stop is erected. The arms or links 24 are spring pressed, as will be seen by reference to Fig. 16, wherein the arm or link 24 is shown pivoted to the iron 12, the end of the arm or link 24 being provided with a socket 26 in which a coiled wire spring 27 is housed. The spring 27 passes around the iron 12 and is secured at its ends to the iron and link 24 respectively, 110 so as to give an upward yielding tension to the arm or link 24. Thus, as the rear bow is lowered or folded, so as to swing the arms or links 24 backwardly and downwardly, the springs 27 will be brought under tension, so 115 that when the top is unfolded or erected the bow will be conveniently brought to position. 120

To the ends of the rear bow 4, there are secured the bow or rib irons 28 which are adapted to engage the uprights or stiles of 125 130

the third or pivoted bow 3, when the top is folded, so as to maintain the third and fourth bows in position.

Each of the bows is provided with a slide way or slide ways for the edges of the respective curtains, and to provide these slide ways the respective bows have been provided with the inner rabbets 29. The first and fourth bows are necessarily only provided with a single rabbet, while the second and third bows are each provided with a pair of rabbets. The rabbets 29 are continuous from one end to the other of the respective bows, and receive the respective edges 15 of curtains as will hereinafter more fully appear. Strips 30 of sheet metal are secured to the inner sides of the bows and have their edges free adjoining the respective rabbets, the edges of the strips 30 being bent back 20 into the rabbets 29 to provide beads 31. It will be understood, of course, that the strips 30 secured to the first and fourth bows, will be provided with only a single bead 31, while the strips 30 of the intermediate bows will 25 each be provided with a pair of beads 31 co-operating with the respective rabbets 29.

As above indicated, each curtain embodies a fabric facing and a flexible metallic frame 16. This frame, reference being had in detail to Fig. 13, embodies a pair of flexible sheet metal sections 32, which are hinged together at their adjoining ends. The sections 32 are provided with openings, and have the flexible transparent panels or panes 17 secured thereto. The fabric or facing of the curtain is provided with openings registering with the openings of the sections 32, so as to provide lights to admit light, and to permit of vision through the curtains. The frame also embodies the flexible edge pieces or strips 33 which extend from end to end along the curtain and to which the edges of the fabric or facing is secured in any well known manner. The remote edges of the sections 32 are hinged or pivoted to the flexible strips 33, the sections 32 and the strips 33 being preferably stamped or otherwise fashioned from sheet metal or other resilient material. The edge strips 33 fit within the respective rabbets 29 of the bows, the beads 31 retaining the strips 33 against inward displacement, and each of the strips 33 is provided with a plurality of instruck tongues or lips 34 engaging in back of the respective bead 31 so as to constrain the strips 33 for sliding movements in the rabbets 29. A finger hold 35 is preferably secured to the lower end of each edge piece 33 of each curtain, in order that the curtain may be readily raised and lowered by hand.

The peak frame 7 embodies a pair of diagonal arms 36 pivoted or hinged to the crown of the front bow 1, folding braces 37 connecting the free ends of the arms 36 and the upper ends of the uprights or stiles of the

bow 1, and a cross piece 38 connecting the free ends of the arms 36 and to which the front edge of the peak 6 is secured. Each of the braces 37 embodies a pair of sections connected by a knuckle joint in order that the 70 same may fold downwardly.

In use, when the top has been erected or unfolded; the respective curtains 13, 14 and 15 may be readily raised and lowered when the entrance ways are to be opened and then closed. When the curtains have been raised or slid upward they will slide into the crowns or intermediate portions of the bows beneath the cover 5, it being noted that both the curtains and frames of the curtains are 80 flexible so as to permit of them being slid under the cover 5. The use of the sliding curtains when the top is erected will be clearly apparent from this brief description, it being noted that the curtains may be slid to such positions as to conform with the various conditions which arise. When both curtains of one pair are slid upwardly, they will abut end to end under the cover 5, as will be apparent. When the top is to be 90 folded or collapsed, all of the curtains are first slid upwardly under the cover 5 or into the crowns of the bows, and the joints of the respective braces 8, 9, 10 and 11 are then broken so as to permit the braces to fold 95 downwardly. The first and second bows are then free to be slid rearwardly on the track 18, the curtains 13 and 14 folding with the respective portions of the cover 5, as it will be noted that the sections 32 of the curtain 100 frames fold together, as well as the facings of the curtains. When the first and second bows have been moved rearwardly the track engaging members or slides 21 will be moved onto the track sections 23 of the 105 irons 22 of the third or pivoted bow. In this manner, the first and second bows are secured to the third bow, and by swinging the said bows rearwardly, the rear or fourth bow may be swung downwardly, as permitted by the arms or links 24, so that the third or pivoted bow may seat on the rear or fourth bow as depicted in Fig. 2. When the bows are thus folded together, the arms or 110 links 24 will support them in folded position. It will also be noted that by breaking the joints of the braces 37, the peak frame may be folded or collapsed against the front bow 1. Thus, in the manner indicated, the top may be readily collapsed, the curtains 115 folding with the cover. The top may again be erected or unfolded in a facile and expeditious manner, by first swinging the third or pivoted bow 3 upward with the first and second bows, and while this is being done, the tension of the arms 24 will swing the rear or fourth bow 4 into position. After the third or pivoted bow 3 has been swung erect, the track extensions of the irons 22 120 will align with the tracks or rail sections. 125

130

The respective braces 8, 9, 10 and 11 may then be straightened or forced upwardly into position, so as to brace the bows or ribs in position and to thereby provide a substantial frame work for the top. As the bows or ribs are unfolded, the respective curtains will unfold with the cover 5, and the curtains will again be in position to be slid downwardly over the sides, to provide 5 a protection against rain, snow and other atmospheric conditions. The peak may also be opened by straightening out the braces 37 as will be evident. The rail engaging members or slides 21 may be retained 10 in position by means of set screws, clamps or any other similar devices, which need not be illustrated or described in detail.

It will be noted that the curtains may not only be slid up and down so as to open and 20 close the entrance ways, and may not only be folded with the bows or ribs, but are also provided with window lights, to admit light into the top and to permit of vision through the curtains when they are lowered. Notwithstanding the provision of the frames 25 for the curtains and window lights, each curtain may readily fold with the cover 5 when the curtains have been slid into the crown of the frame or under the cover 5.

30 From the foregoing, taken in connection with the drawings, the advantages and capabilities of the device will be apparent, it being noted that the objects have been carried out satisfactorily, and that the present top provides a desirable one for the purposes for which it is designed.

In the modifications illustrated in the Figs. 17, 18, and 19, the bows or ribs 2' and 40 3' have been provided with alternate bow or rib irons which may be employed without the tracks, when the vehicle body may not be conveniently provided with the tracks. Thus, the pivoted bow or rib 3' is provided with a bracket or arm 22' which is pivoted 45 to the vehicle body, and the first and second or front bows or ribs 2' are provided with suitable brackets or arms 19' which are attachable to each other and to the brackets or arms 22' of the pivoted bow 3', so that 50 the respective bows or ribs may be attached together when folded, in order to be swung over the rear seat or in back of the body. The details of the bow or rib irons 22' and 19' are of no particular moment and need 55 not be further considered.

If desired, a drop curtain may be carried by the fourth or rear bow 4 to close the rear end of the top, and a similar curtain may be carried by the first or front bow 1, and 60 especially if a wind shield is not employed.

As illustrated in Figs. 20, 21, and 22, the rib or bow 30' is constructed from a strip of sheet metal bent to form opposed slide-ways or guides for the curtains, the rib or 65 bow being of approximately S-shape in

cross section. Thus, the rib or bow is constructed of a strip of metal, and a wooden crown piece 2' is secured upon the outer leaf thereof for the purpose of supporting the cover. With these ribs or bows the cross shaft 9' is attached to the inner leaves, and the folding braces are necessarily disposed on the inner sides of the ribs or bows, as the shafts cannot pass through ribs or bows, which would interfere with the operation of 75 the curtains.

Having thus described the invention, what is claimed as new is:

1. In a vehicle top, a pair of bows adapted to fold together and having slideways therealong, and a curtain embodying flexible sheet metal strips slidably engaging the slideways, two sheet metal frame sections hinged together at adjoining edges and having their remote edges hinged to the said strips, a fabric facing attached to the said strips and sections, the facing and frame sections having registering openings therein, and transparent panels secured to the frame sections over the said openings. 90

2. In a vehicle top, a plurality of bows adapted to fold together, and having rabbits extending from end to end, strips secured to the bows and having beads cooperating with the rabbits, and curtains each embodying a frame and a fabric facing secured thereto, the frame constituting flexible edge strips engaging the respective rabbits and having lips struck therefrom and engaging in back of the respective beads, and flexible hinged window sections hinged to the respective last mentioned strips. 100

3. In a vehicle top, a pivoted bow, a rear bow, rear top irons, folding braces connecting the pivoted bow and the rear bow and top irons, respectively, and links connecting the top irons and the rear bow, the links normally projecting upward from the top irons when the rear bow is erected and being adapted to swing downward to permit the pivoted bow to seat on the rear bow. 105

4. In a vehicle top, a pivoted bow, a rear bow, rear top irons, folding braces connecting the pivoted bow with the rear bow and top irons, respectively, spring pressed links connecting the top irons and the rear bow, and stops carried by the rear bow to engage the said links to limit the forward movement of the rear bow. 115

5. In a vehicle top, a plurality of bows arranged to slide to and from each other, cross shafts carried by the bows, and folding braces connected to the shafts, certain of the brace sections being secured rigidly 125 to the shafts and the other sections being loosely connected to the shafts, to constrain braces at the respective sides to fold in unison.

6. In combination with a vehicle body, 120

tracks carried by the sides thereof, a pivoted bow at the rear ends of the tracks, having attaching means coöoperating with the tracks, bows having means slidably engaging the tracks and attachable to the aforesaid means to swing rearwardly therewith, cross shafts carried by the bows, and folding braces having their ends connected loosely and rigidly to the respective shafts.

10 7. In combination with a vehicle body, tracks carried by the sides thereof, a pivoted bow having track extensions at its pivotal points coöoperating with the aforesaid

tracks, a second bow, and members slidably carried by the second bow and having 15 means slidably engaging the said tracks and adapted to be slid onto the said track extensions.

In testimony that I claim the foregoing as my own, I have hereto affixed my signature in the presence of two witnesses.

JAMES MINOR WORKMAN.
